UNITED STATES PATENT OFFICE.

JACOB FELBEL, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,185,647.

Specification of Letters Patent.

Patented June 6, 1916.

Original application filed October 30, 1915, Serial No. 58,821. Divided and this application filed March 2, 1916. Serial No. 81,646.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

- 10 My present invention relates to universal bar mechanisms for typewriting machines and its main object is to provide new and improved mechanism of the character specified.
- 15 To the above and other ends my present invention consists in the features of construction, combinations of devices and arrangements of parts hereinafter described and particularly pointed out in the claims.
- 20 The present application is a division of my prior application, Serial No. 58,821, filed October 30, 1915.

In the accompanying drawings, Figure 1 is a vertical transverse sectional view of a typewriting machine embodying my invention, parts being omitted. Fig. 2 is a fragmentary perspective view showing the universal bar mechanism and associate parts. Fig. 3 is a fragmentary plan view of the universal bar mechanism. Fig. 4 is a fragmentary perspective view of a modification.

The machine to which my invention is shown applied generally resembles the Monarch typewriting machine but differing in details therefrom, and comprises a main frame which is composed of a base 1, posts 2 and a top plate 3, above which is mounted a slidable platen 4 that is drawn leftward by a spring drum mechanism of ordinary construction (not shown), the leftward movement being controlled by escapement devices which comprise a toothed escapement wheel 5. Coöperative with the escapement wheel are escapement dogs 6 and 7 mounted at the top of a carrier or rocker 8. The dogs are or may be of the usual Monarch construction but in this instance they are reversed from the ordinary arrangement, that is, the rear dog 6 is the stepping or loose dog and the forward dog 7 the fixed dog. The carrier 8 is rocked or swung toward the rear and then forward again to produce step-by-step feed movements of the carriage by universal bar mechanism of

novel construction to be hereinafter described.

Coöperative with the front face of the platen 4 are a circularly arranged series of type bars 9, each type bar having fixed at its free end a block provided with two types, 60 the outer type 10 being the lower case type and the inner type 11 being the upper case type. The type bars may be pivoted on a common pivot wire 12 which is mounted on a shifttable type bar segment or element 13 65 in any well known or desirable manner. The type bars fit in and are partly guided by converging slots in the segment. Each type bar is connected by a link 14 to an upright sub-lever 15 which is pivoted on a 70 key lever 16, said sub-lever being slotted near its lower end to coöperate with a fixed abutment (not shown), but as usual in the Monarch machine. Near their outer end portions the type bars are normally supported by a curved rest 19 which as in the Monarch machine is mounted to shift with the type bar segment 13 during case shifting operations. The connections between said rest and the segment are however not 75 herein illustrated. At its opposite ends or sides said type bar segment is provided with grooved track portions 20 which receive anti-friction balls 21 that are controlled by separators 22, said balls also coöoperating 80 with oppositely grooved track ways 23 that are mounted on stationary posts 24 rising from the base 1. For limiting up and down movements of the segment along the stationary supports or posts, stop devices are 85 provided comprising at each side an upper stop 25 and a lower stop 26 both on the segment itself. Coöperating stop devices 27 and 28 are adjustably secured in pairs to the rear faces of the posts 24. The ball 90 bearing mounting of the segment and the stop devices therefor may be of the usual Monarch construction.

To support the segment 13 and shift it up and down, devices are provided which 100 are connected to lugs or ears 29 extending downward from the segment, one near each end thereof. Said devices comprise a pair of upright links or arms 30, the upper ends of which are pivotally connected at 31 105 to the outer faces of the lugs 29. The lower ends of said links are perforated to engage pivotally with pins 32 that extend laterally

outward from the rear, free ends of crank arms 33. The crank arms have hubs 34 that fit over a key controlled rock shaft 35 and are fixed to said rock shaft near its ends, 6 said rock shaft having stationary bearings. Outside each crank arm there is fixed to said rock shaft a forwardly extending crank arm 36. Fitting loosely over the rock shaft inside each crank arm 36 and extending forward contiguous thereto is an arm 37 which is secured to the crank arm by a screw 38 and provides a bearing at its outer end for a roll 39 that underlies a shift key lever 40, there being two of these shift key 10 levers, one at each side of the machine constructed and operated as set forth in my original application aforesaid. A depression of either shift key lever operates on the underlying roll 39 to swing down the arms 37 and 36, rocking the shaft 35 and swinging the crank arm 33 upward. The upward movement of the crank arms 33 is transmitted through the arms 30 to the type bar support comprising the segment 13, 20 which support is thereby shifted or raised to an extent limited by the engagement of the stops 26 with their associated stops 28.

The result of this shifting movement is to render the upper case types 11 operative 30 when the type bars are actuated, the types 10 having been shifted upward so that they will not strike against the platen. When the actuated shift key is released the type bar segment and connected parts are restored to normal position where the stops 25 engage with their associated stops 27. Counterbalancing springs and shift locking devices as disclosed in my aforesaid original application are preferably provided.

40 The universal bar, according to my present invention, is mounted to reciprocate on a frame or support which in turn is movably mounted on the frame of the machine or a stationary part thereof so that said universal bar support is entirely separate from and independent of the case shifting element or type bar support 13. In the present instance the universal bar support is adapted to be shifted at times automatically upon actuation of either one of the shift keys 40, and means are also provided for disconnecting the universal bar and its support so that the case shifting keys will be ineffective on the universal bar, which at such 50 times will remain in lower case position both when the type bar segment is in lower case position, and also when said type bar segment is shifted to upper case position. The throwing of the universal bar out of 55 the control of the shift keys and its restoration to such control is preferably effected at will through the actuation of a special key. The supporting frame for the universal bar in the present instance comprises an 60 upright segmental plate or body portion 41

which is adapted to fit into the curved opening above the type bar pivots. Said plate is provided with straight, lateral extensions 42 which terminate in forwardly curved lugs 43 in which are fixed downwardly extending pins or bearing devices 44. Fixed to and extending rearward from the plate near its middle is a bearing rod 45 terminating in a head 46 while small bearing pins or devices 47 project rearward from said plate 78 near its ends. The rod 45 and pins 47 provide bearings for a slideable universal bar frame, designated as a whole by the reference numeral 48 and comprising a cross bar or portion 49 provided with a central depression 50 to afford play to the ribbon vibrator (not shown). Fixed to and extending rearward and inward from the cross portion are angular branches 51 and 52 which unite in a rearwardly extending stem 53 provided with a bearing block 54 that fits over and slides on the rod 45. Upright ears 55 at the ends of the cross bar 49 are perforated to fit over the guide pins 47. The end portions of the cross bar are also provided with upwardly extending ears 49^a to which are fixed a universal bar proper 56, said universal bar being arcuate in shape and being arranged close to the edge of the supporting plate or frame 41. Said universal bar is provided with an upturned ledge or lip which is adapted to be actuated directly by shoulders 9^a on the type bars 9. The universal bar is normally maintained forward with the ears 55 in contact with the rear face of the plate 41 by a coiled spring 57 which is connected at its rear end to the universal bar frame and at its front is anchored to said plate. Movements of the universal bar when actuated are limited by the head 46.

To support and guide the frame 41, 42 and the universal bar devices carried by said frame, a pair of brackets 58 are provided, one secured to each of the posts 24 at its upper front side by screws 59. Each bracket has an ear 60 perforated to receive one of the guide pins 44, the construction permitting a slideable up and down movement of the universal bar and its supporting frame 11^a parallel with shifting movements of the type bar segment. When mounted in place the frame 41 is in the curve of the type bar segment, the lateral portions 42 extending over the ends of said segment while the universal bar proper is arranged between the top of the type bar segment and the curved bottom of the plate 41 and so located that its upturned edge is above the type bar pivots when in normal position. The universal bar frame is connected with the dog carrier 8 in order to transmit movement from the type bar to said dog carrier by a link or rod 61 which is loosely connected at its rear with the dog carrier by means of a screw 62. At 18^a

its forward end the rod 61 is pivotally connected with the universal bar frame 48. It will be understood that when one of the type bars is operated its shoulder 9^a will, toward the end of the stroke, hit the universal bar proper 56 and slide the universal bar frame rearward, overcoming the spring 57, this movement being independent of the supporting frame 41, 42 and being transmitted through the rod or connector 61 to the carrier 8, causing the latter to swing rearward, disengaging the dog 6 from the escapement wheel 5 and bringing the dog 7 into engagement therewith. When the printing key is released the parts will be restored to normal position by the restoring springs, the dog 7 moving out of the escapement wheel and the dog 6 reengaging therewith at the next succeeding tooth. As a result of this reciprocation of the escapement devices the carriage will advance a letter space distance toward the left under the pull of the spring drum or motor. A center type guide 63 of ordinary construction is fixed to the universal bar supporting frame 41, 42 and shifts therewith. The type end of each type bar cooperates with said guide near the end of its stroke and at the printing moment.

The means for automatically shifting the universal bar when the case shifting mechanism is operated by one of the shift key levers 40 comprise connections between the support or frame 41, 42, and the rock shaft 35. Said connections include upright arms 64 pivotally connected by shoulder screws 65 to the side portions 42 of the supporting frame. The lower ends of the arms 64 are formed with eyes which receive flanged bearing blocks 66 that are held in place by caps 67. These bearing blocks are provided with downwardly extending lugs 68 having rounded heads and said bearing blocks 66 are perforated to fit loosely over the pins or studs 32 outside the arms 30. Stationary pins or rods 70 fixed to the sides of the base and projecting laterally inward therefrom in register with or in line with the studs 32 terminate just short of the bearing blocks 66 so as not to interfere with the up and down movements of said bearing blocks when the rock shaft 35 is rocked. These rods 70 are of the same diameter as the studs 32 and are adapted to receive and support the bearing blocks when the latter are slid outward by means presently to be described for the purpose of disconnecting the universal bar from the case shifting mechanism. The ends of the studs 32 and of the rod 70 are preferably beveled or tapered slightly to facilitate the lateral connecting and disconnecting movements of the bearing blocks and the arms 64 which carry them.

The disconnecting means comprise levers 71 and 72 pivoted at 73 on angular brackets

74 screwed or otherwise secured to the base frame 1 and extending inward therefrom. The pivots 73 are below the lugs 68. The right-hand lever 71 is a bell crank and has an upright arm 75 provided with a vertical opening or slot indicated at 76 which engages loosely with the rounded end of the associate lug 68. The other arm 77 of the bell crank extends horizontally outward and underlies a downward extension 78 on a special key lever 79 pivoted in the rear of the base and provided with a key 80 which is disposed at the right-hand side of the keyboard. The left-hand lever 72 is substantially upright, comprising an upper slotted arm 81 which loosely engages with the left-hand lug 68, said lever further comprising a downwardly extending arm 82.

The lever arms 75 and 82 are operatively connected by a link or rod 83. The construction is such that when the special key 80 is operated the extension 78, acting against the arm 77, will rock the bell crank 71 and through the rod 83 will also rock the lever 72. The upwardly extending arms of said lever will swing outward away from each other and will act to shift the bearing blocks 66 laterally outward on to the stationary pins 70, thus disconnecting the arms 64 from the studs 32 as illustrated by dotted lines in Fig. 1. Following such disconnection it will be understood that an operation of either of the shift key levers 40 will be effective to shift the type bar segment 13 but not the universal bar 56 nor its carrier frame 48, these parts remaining down in lower case position. In order to reconnect the disconnected parts, means are provided comprising a sleeve 84 that is slidably mounted on the left-hand rod 70. Connected with the sleeve or slide 84 is a push rod 85 that passes loosely through an opening 86 in the left-hand side of the base 1 and is provided outside the base with a key or button 87. A coiled spring 88 anchored to said base tends constantly to draw the sleeve toward the left, its movement in this direction being limited by a cross pin or stop 89 on the rod 85. This stop arrests the sleeve in such position that its right-hand end is close to the left-hand bearing block 66 when the bearing blocks have been set on the rods 70. Consequently by pushing in the key 87 at this time the sleeve will contact with the left-hand bearing block 120 and force it back on to its stud 32. This movement of said bearing block operates through its lug 68 on a train of devices comprising the lever 72, rod or link 83 and lever 71 to restore the right-hand bearing block 66 to engagement with its stud 32. On releasing the key 87 the spring 88 will restore the sleeve to its left-hand position. A stop device 90 may be provided for limiting the movements of the disconnecting de-

vices. Said stop device is secured by a screw 91 to the right-hand bracket 74 and has stopping faces 92 and 93 that project into the path of the lever arm 77 above and below the same to limit its movements in both directions, and thus limit also the movements of the devices with which it is connected and which it controls.

A modification of the construction is illustrated in Fig. 4 wherein the lever 79 is replaced by a lever 94 pivoted at the rear of the base and provided with the usual restoring spring and finger key. Said lever 94 is provided with a downward extension 95 which at its lower end is formed with a slot indicated at 96 in which is loosely engaged the lever arm 77. When the special key lever 94 is depressed the top of the slot 96 engages with the lever arm to rock it and swing the right-hand bearing block 66 on to its rod 70. At the same time through the link 83 the lever 72 is caused to swing the left-hand bearing block to its inoperative position on its rod 70. While the lever 94 is maintained depressed by one finger, the operator may, with the finger of the same hand, depress the right-hand shift key 40 which is in juxtaposition to the key of the lever 94. This leaves the left-hand free to operate the printing keys. On releasing the key lever 94 its spring will restore it to normal position and the bottom of the slot 96 engaging with the under side of the lever arm 77 will operate on the train of devices connected with said lever arm to restore the bearing blocks to engagement with their studs.

Preferably the special key lever 94 is provided with a locking key of suitable construction, such as that found on the left-hand shift key lever of the No. 10 Remington machine, by which locking key said special lever may be locked down to maintain the universal bar 56 withdrawn from the control of the shift key mechanism as long as may be desired.

It will be observed that the center-guide 63 is supported independently of the case shifting element, type bar support or segment 13; that said center guide is shiftable simultaneously with said element to change case position; that said center guide is also shiftable independently of said element; and that said center guide and the support 55 on which it is mounted, which is also the support of the universal bar, are shiftable from upper case to lower case position while said element or type bar support remains quiescent.

Various changes besides those specified may be made without departing from the spirit and scope of my invention.

What I claim as new and desire to secure by Letters Patent, is:

1. In a typewriting machine, the combi-

nation of a shiftable type bar support, a universal bar support connected to be shifted concurrently therewith, and means for at will changing the universal bar support connections and permitting the universal bar support to remain stationary while the type bar support is shifted alone.

2. In a typewriting machine, the combination of a type bar support, a universal bar support, shifting mechanism, independent connections from said supports to said shifting mechanism whereby the two supports can be shifted concurrently, and means for detaching the universal bar support connections from the shifting mechanism so that when desired the type bar support may be shifted alone.

3. In a typewriting machine, the combination of a type bar support, a universal bar support, mechanism for shifting said supports concurrently, means for disconnecting the universal bar support from the shifting mechanism, and means for holding the universal bar support stationary while the type bar support is shifted.

4. In a typewriting machine, the combination of a type bar support, a universal bar support, a shifting mechanism, independent connecting devices between said supports and said shifting mechanism, means for disconnecting the universal bar support connecting devices from the shifting mechanism, and stationary devices for receiving said connecting devices when so disconnected from the said shifting mechanism whereby the universal bar support may be prevented from shifting when the type bar support is shifted.

5. In a typewriting machine, the combination of a shiftable type bar support, a shiftable frame mounted independently of said type bar support, a universal bar supported by said frame and movable relatively thereto, key controlled devices for shifting said support and said frame comprising separate links, and means for disconnecting certain of said links so that said shiftable frame is disconnected from said key controlled devices.

6. In a typewriting machine, the combination of a shiftable type bar support, a shiftable universal bar, a key operated rock shaft, devices comprising a link connecting said support with said rock shaft, other devices comprising a second link connecting said universal bar with said rock shaft, and means for disconnecting said second link from said rock shaft, said last named means comprising a lever having loose connections with said second link and a key for actuating said lever.

7. In a typewriting machine, the combination of a shiftable type bar support, a shiftable universal bar, a key operated rock shaft, crank arms on said rock shaft near

- its ends, a pair of links connecting said support with said crank arms, devices comprising a second pair of links connecting said universal bar with said crank arms, and
- 6 means for disconnecting said second pair of links from said crank arms, said means comprising a pair of levers each having a loose connection with one of said links, a connecting rod connecting said pair of
- 10 levers, and a key lever operative on one of said levers.
8. In a typewriting machine, the combination with case shifting mechanism comprising a key controlled shiftable element, of a universal bar mounted independently of said element, connections between said universal bar and said element, and key operated means for breaking said connections at will.
- 20 9. In a typewriting machine, the combination of a case shifting element, a universal bar, a key operated rock shaft provided with crank arms, devices comprising a pair of links connecting said universal bar
- 25 with said crank arms, means for disconnecting said links from said crank arms, said means comprising a pair of connected levers each having a loose connection with one of said links, and a key lever operative
- 30 to actuate one of said levers.
10. In a typewriting machine, the combination of a case shifting element, a universal bar, a key operated rock shaft provided with crank arms, devices comprising
- 35 a pair of links connecting said universal bar with said crank arms, means for disconnecting said links from said crank arms, said means comprising a pair of connected levers each having a loose connection with
- 40 one of said links, a key lever operative to actuate one of said levers, and re-connecting means comprising a key operated slide effective on one of said links.
11. In a typewriting machine, the combination of a case shifting element, a universal bar, a key operated rock shaft provided with crank arms, devices comprising a pair of links connecting said universal bar with
- 45 said crank arms, and means for disconnecting and re-connecting said pair of links with said crank arms, said means comprising a pair of connected levers each loosely connected with one of said links, and a key lever having a loose connection with one of
- 50 said levers and effective on its down and up strokes to move said one of said levers oppositely.
12. In a typewriting machine, the combination of a shiftable type bar segment, a universal bar normally shiftable therewith, an escapement mechanism operative by said universal bar, and means whereby the universal bar may be prevented from shifting with the type bar segment.
- 55 13. In a typewriting machine, the combination of a shiftable type bar support, a universal frame, a universal bar mounted on said frame and movable relatively thereto, a key controlled element, a link connecting said support with said element, a second link connecting said frame with said element, and means for affording relative displacement between said second link and said element.
14. In a typewriting machine, the combination of a shiftable type bar support, a shiftable frame, a universal bar mounted on said frame and movable relatively thereto, a key controlled rock shaft, a crank arm on said rock shaft having a lateral stud or pin, a link connecting said support with said crank arm, a second link connecting said frame with said stud, and means for affording relative displacement between said second link and said stud.
15. In a typewriting machine, the combination of a shiftable type bar support, a universal bar support adapted to shift concurrently therewith, and means whereby at will the type bar support may be shifted without shifting the universal bar support.
16. In a typewriting machine, the combination with case shifting mechanism comprising a key controlled shiftable element, of a universal bar mounted independently of said element, means for automatically shifting said universal bar when said element is shifted, and means for rendering said automatic shifting means inoperative.
17. In a typewriting machine, the combination with case shifting mechanism comprising a key controlled shiftable element, of a universal bar, a shift key, connections from said shift key both to said universal bar and also to said element, and means for rendering said shift key ineffective to shift said universal bar when said element is shifted.
18. In a typewriting machine, the combination of a platen, type bars, case shifting mechanism including a shift key for effecting a relative shifting movement between said platen and said type bars, a universal bar mounted on the frame of the machine and operative directly by said type bars, escapement devices connected to said universal bar, connecting devices between said universal bar and said shift key, and means for rendering said connecting devices ineffective.
19. In a typewriting machine, the combination of a shiftable type bar support, a universal bar, a center guide for the types, means for supporting said universal bar and said center guide independently of said type bar support, and means controlled by a single key for simultaneously shifting said support, said universal bar and said center guide.
20. In a typewriting machine, the combination of a shiftable type bar support, a universal frame, a universal bar mounted on said frame and movable relatively thereto, a key controlled element, a link connecting said support with said element, a second link connecting said frame with said element, and means for affording relative displacement between said second link and said element.

6
nation of a shiftable type bar support, a universal bar, a center guide for the types, means for supporting said universal bar and said center guide independently of said type 5 bar support, means controlled by a single key for simultaneously shifting said support, said universal bar and said center guide, and means for shifting said universal bar and said center guide while said 10 support remains quiescent.

21. In a typewriting machine, the combination of a case shifting element, a center

guide, means for simultaneously shifting said element and said center guide, and means for shifting said center guide independently of said case shifting element. 15

Signed in the borough of Manhattan, city of New York, in the county of New York, and State of New York, this 1st day of March, A. D. 1916.

JACOB FELBEL.
